(57) **CLAIM**

The ornamental design for an electronic hybrid switch for resistive loads, as shown and described.

DESCRIPTION

1. Commutator [electricity]

1.1 : Perspective

1.2 : Front

1.3 : Back

1.4 : Right

1.5 : Left

1.6 : Bottom

1.7 : Top

The broken lines in the drawings depict portions of the electronic hybrid switch for resistive loads that form no part of the claimed design.
